[57] CLAIM

The ornamental design for a anthropometric caliper, as shown and described.

DESCRIPTION

FIG. 1 is a perspective view of a anthropometric caliper showing my new design;

FIG. 2 is an enlarged fragmentary view thereof, shown with the caliper arm in an alternate position;

FIG. 3 is a rear elevational view;

FIG. 4 is a top plan view;

FIG. 5 is a bottom plan view;

FIG. 6 is a left side elevational view; and,

FIG. 7 is a right side elevational view thereof.
